UNITED STATES PATENT OFFICE.

ISAAC W. FRANK, OF PITTSBURGH, PENNSYLVANIA, ASSIGNOR TO UNITED ENGINEERING & FOUNDRY COMPANY, OF PITTSBURGH, PENNSYLVANIA, A CORPORATION OF PENNSYLVANIA.

SHEARS.

1,140,897.

Specification of Letters Patent. Patented May 25, 1915.

Application filed March 20, 1915. Serial No. 15,750.

To all whom it may concern:

Be it known that I, ISAAC W. FRANK, a citizen of the United States, residing at Pittsburgh, in the county of Allegheny and 5 State of Pennsylvania, have invented a new and useful Improvement in Shears, of which the following is a full, clear, and exact description, reference being had to the accompanying drawings, forming part of 10 this specification, in which—

Figure 1 is a side elevation, partly broken away, of a shear embodying my invention. Figs. 2 and 3 are sectional detail views illustrating two different forms of my invention. 15 Fig. 4 is a transverse section of the shear block shown in Fig. 2. Fig. 5 is a longitudinal section thereof. Fig. 6 is a top plan view thereof, and Fig. 7 is a broken section showing the breaker block applied to the 20 movable jaw.

My invention relates to shears, and particularly shears of the lever or "alligator jaw" type. In shears of this type the lever jaw which carries the movable shear blade 25 is frequently broken by reason of excessive strains, such as may be caused by the wedging between the blades of a piece being sheared. This necessitates expensive 30 repairs.

The object of my invention is to provide means of simple and effective character for preventing such breakage. I accomplish this object by providing a breaker block in 35 one of the jaws, and preferably between the fixed shear blade and the bed of the machine. This frangible block constitutes the weakest point in the structure when subjected to the wedging action previously described, so that in case of excessive wedging 40 strains it gives way and relieves the strains on the other parts. Being of simple, inexpensive character, the block can be readily and cheaply replaced.

In the accompanying drawing, referring 45 to Figs. 1 to 6, inclusive, the numeral 2 designates the frame and bed of a lever shear, 3 the fixed shear blade, and 4 the lever or jaw carrying the movable shear blade 5. 6 designates the driving motor, and 7 the actuating gearing. The shear may be in general of any well known construction and need not be described in detail. 8 is the breaker block which is seated 50 between the fixed shear blade 3 and the abutment 9 on the bed 2, being secured by

any suitable means, as by the bolts 10, which also hold the blade 3. This block is shown as of general inverted U-shape in cross section, its depending legs being perforated for bolts 10. It is preferably made 60 of cast iron or other material which will break readily under excessive strains, such as would be caused by the wedging of a piece between the blades 3 and 5. 11 designates a liner plate on which the blade 3 and 65 breaker block 8 are seated. The upper surface of the block 8 is preferably concaved, as indicated at 12, for the purpose of protecting it against undue downward pressure due to some projection, such as a projecting 70 rivet head on the piece being sheared. The block may be reinforced by the internal webs 14. These are shown as obliquely arranged (Fig. 6) to reduce their effective resistance to crushing strains. 75

In Fig. 3 I have shown a modified form of breaker block in which the legs 13 bear at their ends against the abutment 9^a. That is to say, the block is placed with the legs 80 extending horizontally instead of vertically.

In Fig. 7 I show another form of the invention in which, instead of applying the breaker block to the fixed jaw, I apply it to the movable jaw 4^a. In this form the construction is preferably generally the same 85 as in the first form, 8^a being the U-shaped breaker block, 11^a the liner plate, 5^a the blade, and 10^a the bolts passing through the blade, the breaker block, and the movable jaw. 90

The advantages of my invention will be readily apparent since it provides a simple and effective expedient whereby breakage of the working parts of the shear is prevented. When the breaker block gives way 95 it can be readily and quickly replaced at comparatively small expense.

I do not desire to limit myself to the particular forms and arrangement of the breaker block as herein shown and described, as it is obvious that the form and arrangement may be changed in various ways without departing from the spirit and scope of my invention as defined in the appended claims. 100 105

I claim:

1. A shear having one of its jaws provided with a frangible breaker block interposed between the blade and the rear part of the jaw, said block being adapted to give 110

- way under excessive pressure in a direction at substantially right angles to the plane of the shear blades; substantially as described.
5. A shear having one of its jaws provided with a frangible breaker block interposed between the blade and the rear part of the jaw, said block being arranged to give way under excessive wedging action 10 between the blades; substantially as described.
3. A shear of the lever or alligator type, having one of its jaws provided with a frangible breaker block seated removably 15 behind its blade, said block being arranged to give way under excessive wedging action between the blades; substantially as described.
4. A shear of the lever or alligator jaw 20 type, having means for protecting the lever jaw against breakage, said means comprising a frangible member interposed between one of its shear blades and the lateral abutment for said blade, said member being capable of breaking when subjected to an excessive strain due to a wedging action of 25 said blade; substantially as described.
5. A shear having a breaker block interposed laterally between its fixed blade and an abutment on the shear bed, and a single securing means for both the shear blade and the breaker block, substantially as described.
- 30 6. A shear having one of its jaws pro-
- vided with a frangible breaker block interposed laterally between the blade and the rear part of the jaw, and a single securing means for both the blade and the breaker block; substantially as described.
7. A shear having a frangible breaker 40 block interposed laterally between its fixed blade and the bed of the shear, said block having a recessed upper surface, substantially as described.
8. A shear having one of its jaws provided with a frangible breaker block interposed laterally between the blade and the rear part of the jaw, said member being hollow with obliquely arranged internal webs; substantially as described.
- 45 9. A shear having a hollow breakable member interposed laterally between its fixed blade and the bed of the shear, said member having a recessed upper surface, substantially as described.
- 50 10. A shear having a hollow breakable member interposed laterally between its fixed blade and the bed of the shear, said member having a recessed upper surface and having obliquely arranged internal 55 webs, substantially as described.
- 55 In testimony whereof, I have hereunto set my hand.
- ISAAC W. FRANK.
